UNITED STATES PATENT OFFICE.

ALEXANDER GEORGE MACKENZIE JACK, OF BRINCLIFFE, SHEFFIELD, ENGLAND,

CAP FOR ARMOR-PIERCING PROJECTILES.

987,073.

Specification of Letters Patent. Patented Mar. 14, 1911.

Application filed April 13, 1910. Serial No. 555,133.

To all whom it may concern:

Be it known that I, ALEXANDER GEORGE MACKENZIE JACK, a subject of the King of Great Britain and Ireland, residing at Brincliffe, Sheffield, in the county of York, England, have invented Improvements in Caps for Armor-Piercing Projectiles, of which the following is a specification.

This invention has reference to metal caps of the kind adapted to fit over and around the pointed nose of an armor piercing projectile and having integral therewith a hollow point or forward extension.

The invention has for object to provide an improved construction of cap of this kind whereby the point of the projectile to which it is applied can be supported against rupture in a better manner than heretofore usual. For this purpose the cap proper is so shaped on its forward end and so united to its hollow point or forward extension that when the cap is fitted to a projectile and the projectile fired at an armor plate, pressure transmitted to the solid front end portion of the cap proper upon its hollow forward extension striking the plate will cause such solid front end portion to press in an inward instead of an outward direction upon and around the pointed end portion of the projectile and thereby support such portion of the projectile in a more effective manner than heretofore usual, against fracture, upon contact with the plate.

To enable a hollow pointed cap to act in this manner, the front end portion of the cap proper is made of concave or inverted conical or equivalent cup shape and the base or rear end portion of the hollow point which is integral with the cap, is made of gradually increasing thickness rearward and on its inside with a curved surface of large radius merging into the surface of the cupped recess in the front end of the cap so as to form a connecting portion between the cap and hollow point of gradually increasing thickness and strength in a rearward direction. Upon a projectile fitted with such a hollow pointed cap striking an armor plate and the hollow point of the cap flattening, pressure upon the thickened edge portion of the concave or cupped front end of the cap proper will cause the cap not only to support the point of the shell but further it will also cause the cap to exert an inward or constrictive pressure at and around the point of the projectile and thus prevent or assist in preventing rupture of

such point and consequent rupture of the entire shell when the same reaches the plate.

The hollow point or forward extension of the cap may be of any desired dimensions and of any suitable or desired shape externally, as for example ogival, of any desired radius or radii, or conical, with an extreme front end of pointed, rounded or other shape as may be required and as well understood. Internally, the hollow point may be of a shape that conforms more or less to that of its exterior and of such size that the wall constituting the hollow point, or extension, is comparatively thin for the greater part but the base portion thereof, where it joins the body of the cap, is as hereinbefore mentioned, made of gradually increasing thickness in a rearward direction, and with a large internal radius or curvature so as to strengthen the connection between the point and cap and minimize risk of fracture at this part when the capped projectile strikes an armor plate.

In the accompanying illustrative drawings, Figure 1 shows the ogival pointed front end portion of an armor piercing projectile fitted with a hollow pointed cap constructed according to the present invention, the projectile being shown in side elevation and the cap in central longitudinal section. Figs. 2, 3 and 4 are similar views to Fig. 1 showing modified forms of caps.

In Fig. 1, the metal cap *a* is formed with a comparatively short hollow pointed portion *b* that is integral with the cap proper, the portions *c* uniting the cap proper with its hollow point being made comparatively thick and with a large internal radius at *d* for the purpose hereinbefore explained, the remainder of the wall being comparatively thin and therefore capable of readily flattening or collapsing. In the example now being described, the hollow pointed cap is formed with an obtuse angled conical front end portion *e* connected by a curved or ogival surface *f* with the conical rear end surface *g*, the general external formation and relative dimensions of the hollow pointed cap being, for a particular caliber of the projectile, substantially those of the solid cap described in the specification of British Letters Patent No. 19104 of 1907. The solid front end portion of the cap *a* is here shown as made, for the purpose hereinbefore described, with a recess *h* of inverted conical or concave shape and the surface of

which gradually merges into that of the comparatively thin wall of the hollow point *b*. The rear side of the cap is shaped as usual to closely fit the projectile *i* with which the cap is to be used.

Fig. 2 shows a cap with a hollow point *b* and coned, cupped or concave shaped recess *h* as in Fig. 1, but the point *b* is made longer and of ogival shape while the external shape 10 of the cap proper *a* is made with a large radius of curvature, say equal to about five times the caliber of the projectile, or more, to facilitate flight of the capped projectile, as now well understood.

Fig. 3 shows a similar construction of cap to that shown in Fig. 2 except that the exterior of the cap with its hollow point is made with a single large radius of curvature, for the purpose mentioned.

Fig. 4 shows a modification in which the exterior of the cap *a* and its hollow point *b* is of conical shape throughout except at the extreme point which is of rounded shape.

When a projectile provided with a cap 25 constructed as described strikes a hard faced armor plate, the hollow forward portion of the cap will exert great pressure through the thickened edge portion *c* of the cap upon the cap proper and tend to force the metal 30 of the cap inward upon the pointed end portion of the projectile so as to support the same against fracture. The hollow forward portion of the cap will not however be at once dispersed or separated from the cap 35 proper but will on the contrary be caused to assume a flattened or collapsed shape as approximately indicated in dotted lines in Fig. 2, so as to form a surrounding strengthening ring *b*¹ which will delay the breaking up of 40 the cap *a* and will moreover further reinforce the supporting and constrictive action of the cap around the pointed portion of the projectile *i* in a manner which is not possible when the cap is provided at its front end 45 with a flat convex or forwardly projecting conical surface, and when the hollow pointed or forward extension of the cap is made separate from the cap proper and mechanically attached thereto. The above mentioned action of the improved cap has been confirmed in a striking manner in several instances. Thus, in recent tests carried out 50 with six inch armor piercing projectiles fitted with hollow pointed caps constructed according to this invention and with solid caps, both kinds of caps being externally of exactly the same shape and dimensions, it was found that the projectile fitted with the solid cap when fired at a low velocity, 55 namely below 1900 feet per second, against a Krupp cemented plate of a thickness equal to the diameter of the projectile did not succeed in perforating the plate and was broken up on the surface of the plate whereas a projectile fitted with the hollow pointed cap 60

when fired not only succeeded in completely perforating the plate at a still lower velocity but was afterward recovered in an unbroken condition.

A hollow pointed cap such as described 71 can be constructed by forming the cap proper *a* with a hollow forward extension, such as is indicated in dotted lines at *b*² in Figs. 1 and 2, of more or less cylindrical or other shape, open at its front end and closed at its rear end by the front end portion of the cap proper which is preferably made of the concave or inverted hollow conical shape hereinbefore referred to, the hollow forward extension *b*², which may be of approximately 76 equal or tapering thickness, being afterward closed in under pressure, as by a suitable die or dies, as for example a cupped die *h*, also shown in dotted lines in Fig. 1, to form a hollow closed point or extension of 81 the desired shape. The hollow forward extension *b*² of the metal cap *a* may, if desired, be heated to facilitate its being closed in, or it may be closed in while in the cold state.

What I claim is:—

1. A cap adapted to fit closely over and around the pointed nose of an armor piercing projectile and having a recessed front end surface and a hollow point that extends forward from the marginal edge portion of the said recessed front end of the cap and is integral therewith.

2. A cap adapted to fit over and around the pointed nose of an armor piercing projectile and having a recessed front end surface covered by a hollow point or forward extension the rear end portion of which is united integrally with the marginal edge portion of the recessed front end of the cap by a connecting portion of gradually increasing thickness and strength in a rearward direction.

3. A cap provided with a solid rear portion adapted to fit over and around the pointed nose of an armor piercing projectile, said solid rear portion having a recess in its front surface, and a hollow point extending forwardly from and integral with said solid rear portion, the inner surfaces of the recess and of the hollow in the point being merged one into the other by a curved surface having a comparatively large radius.

4. A cap having a solid rear portion adapted to fit over and around and support the pointed nose of an armor piercing projectile and having a recess in the front surface of said rear portion and a hollow point covering the said recess and integral with the cap and of ogival shape externally, said hollow point being made thin for the greater part of its length but of gradually increasing thickness at the part where it joins the recessed front end portion of the cap substantially as described and shown.

5. For an armor piercing projectile hav

ing a pointed nose, a cap adapted to fit around and support the pointed nose of the projectile and having a hollow point or forward extension integral with the cap proper and a front end surface of cupped shape covered by said hollow point and the surface of which gradually merges into the inner surface of the hollow point, the inner curved surface of the connected parts having a comparatively larger radius.

6. A metal cap recessed on its rear side to fit over and around the pointed nose of an armor piercing projectile and having at its solid front end portion a recess of inverted 15 conical shape and a hollow point integral with the cap and covering the recessed front end thereof, the surfaces of the recessed front end portion of the cap and of the interior of the hollow point gradually merging one into the other, substantially as described for the purpose set forth.

7. A cap for an armor piercing projectile having a solid front end portion recessed on its rear side to fit over, around and support the pointed nose of a projectile and formed on its front side with a recess of 25 conical shape and with a hollow point that extends beyond and covers the recessed front end portion of the cap and is integral with 30 the marginal edge portion thereof, the metal

at the junction of the two parts being of gradually increasing thickness in a rearward direction.

8. A one-piece, integral cap having a solid rear portion adapted to fit snugly over and around the pointed nose of an armor piercing projectile and having a hollow, forwardly extending point.

9. A one-piece integral cap having a solid rear portion and a wall of gradually diminishing thickness rearwardly extending therefrom, said rear portion and said wall being adapted to fit closely over and around the pointed nose of a projectile, and said cap having a hollow point forwardly extending 40 from said rear portion.

10. A one-piece integral cap having a solid rear portion adapted to fit snugly over and around the pointed nose of a projectile, and a hollow point forwardly extending 50 from the solid rear portion, a wall forming said hollow point and connecting the same to the rear portion being thickened where it joins the rear portion.

Signed at Hecla Works, Sheffield, Yorkshire, England this 22nd day of March 1910.

ALEXANDER GEORGE MACKENZIE JACK.
